UNITED STATES PATENT OFFICE

2,634,440

SHOE STRAIGHTENER

Brother E. Walstrom, Dunedin, Fla.

Application May 8, 1951, Serial No. 225,123

2 Claims. (Cl. 12—129.1)

1

My present invention relates generally to a shoe form, and, more specifically, is directed to a shoe form for supporting shoes when not in use, whereby the latter may be maintained in proper shape.

The shoe form of my present invention is an improvement over the shoe form disclosed in Patent No. 2,319,650, which was issued in my name on May 18, 1943.

It is an object of my present invention to provide a shoe form which is adapted to maintain the sole of a shoe perfectly flat in order that the vamp of the shoe may be held against creasing or wrinkling and the shoe retained in proper shape.

A feature of the shoe form of my present invention resides in the provision of a base portion and a pair of convergent channels, one of which is fixed and the other one of which is pivotally mounted to the base portion. The channels are adapted to receive the sole of a shoe for clamping the latter in a flat position. A shoe form of the character noted, embodying the movable channel, can accommodate a wider range of shoe sizes and sole shapes than present known shoe forms can accommodate.

A further feature of my present invention resides in the provision of a spring clamp secured to the rear end of the base portion of the shoe form which is adapted to engage the edges of the sole of the shoe adjacent the rear shank portion immediately forwardly of the forward edge of the heel of the shoe. The spring clamp tends to maintain the shoe straight in order to prevent creasing or wrinkling of the vamp of the shoe.

Now, in order to acquaint those skilled in the art with the manner of constructing and using the device of my present invention, I shall describe in connection with the accompanying drawings, a preferred embodiment of my invention.

In the drawing:

Figure 1 is a plan view of the shoe form of my present invention;

Figure 2 is a side elevational view of the shoe form of Figure 1 and illustrates a shoe in position in the form;

Figure 3 is a sectional view taken substantially along the line 3—3 in Figure 1 looking in the direction indicated by the arrows; and

Figure 4 is a sectional view taken substantially along the line 4—4 in Figure 1 looking in the direction indicated by the arrows.

Referring now to the drawing, there is indicated generally by the reference numeral 10, the

2

shoe form of my present invention which comprises a planar base portion 11 the contour of which conforms substantially to the general outline of the sole of a shoe. The base portion 11 has a lateral portion 9, a toe portion 12, and a rear end portion 13.

The base portion 11 adjacent one edge thereof is formed with an upturned vertically extending flange portion 14 which at its upper end is bent inwardly as at 15 defining a fixed channel 16, which along its longitudinal extent is arcuate in shape.

A clamp member 17 is pivotally mounted at 18 to the lateral portion 9 of the base 11. The inner edge of the clamp member 17 is formed with an upturned vertically extending flange portion 19 which at its upper edge is bent inwardly as at 20. The flange 19, together with the base portion 11, defines a movable channel 21, which along its longitudinal extent is arcuate in shape.

An arcuate slot 22 is formed in the clamp member 17 and projecting upwardly through the slot 22 is a lug 23 which is suitably mounted to the base 11. The lug portion 23 is formed with laterally extending fingers 24 which engage the upper surface of the clamp member 17 and serve as a guide for the latter during pivotal movement about the axis 18.

A helical torsion spring 25 having two free ends 26 and 27 is secured to the clamp member 17 intermediate of the ends thereof. The end 26 of the spring 25 is disposed in engagement with the lug 23 of the base 11 while the end 27 is disposed in engagement with a lug 28 formed integrally with the clamp member 17. The spring 25 causes the clamp member 17 to be normally biased inwardly about the pivot point 18.

A suitable spring clamp 30 is arranged transversely of the rear end portion 13 of base 11 and is suitably secured thereto intermediate its ends as by a rivet 31.

In Figure 2, a shoe 33 is shown fitted within the shoe form 10 of my present invention. It will be apparent to those skilled in the art that in fitting the shoe to the shoe form, the edge of the sole 34 of the shoe 33 is forced forwardly into the channels 16 and 21. As the shoe is moved forwardly the clamp member 17 pivots outwardly about pin 18 against the clamping force of the spring 25. With the sole of the shoe firmly clamped within the channels, it will be noted that the rear end portion 13 of the base 11 terminates adjacent the rear shank portion of the shoe immediately forwardly of the forward edge 35 of the heel 35. Pressure is then exerted down-

wardly on the shoe adjacent the rear end thereof until the spring clamp 30 snaps into engagement with the edges of the sole 34. The shoe is now securely clamped to the shoe form.

With the shoe 33 mounted in the shoe form 10 as shown in Figure 2, all wrinkles or creases in the vamp portion 36 of the shoe are removed and the sole 34 is firmly clamped in a flat position. If the shoe has become wet and it is placed in the shoe form, the shoe will dry in its natural shape and the sole will be maintained flat.

Airing of the sole 34 of the shoe 33 when clamped in the shoe form may be accomplished, for example, by forming a plurality of vents or openings 32 in the base 11. Airing of the sole may be accomplished in other ways, as for example, by forming elevated ridges in the base 11.

The contour of the base 11 obviously may be varied to accommodate shoes of various sizes and sole shapes. It will also be obvious to those skilled in the art that the shoe form may be made of any suitable material, as, for example, lightweight metal, wood, plastic or any material which has sufficient rigidity to maintain its shape under stress, and which can be readily molded or fabricated to the desired shape. It is to be also noted that the depth of the channels 16 and 21 may be varied to accommodate various sole thicknesses.

Now, while I have shown and described what I believe to be a preferred embodiment of my present invention, it will be understood that various modifications and rearrangements may be made therein without departing from the spirit and scope of my present invention.

I claim:

1. A shoe form comprising a planar base portion of rigid material having a contour substantially the shape of a shoe sole, an upturned vertically extending flange formed integrally with said base portion along one edge thereof, said flange at its upper edge being bent inwardly of said base portion for defining a fixed channel, a clamp member pivotally mounted at its forward end to said base portion, said clamp member having formed integrally therewith an upturned vertically extending flange portion which at its upper end is bent inwardly for defining a movable channel, said fixed and movable channels converging toward the toe portion of said base, a horizontally extending slot formed in said clamp member, a lug secured to said base portion and extending upwardly through said slot in said clamp member, said lug having laterally extending arm portions which engage the

upper surface of said clamp member for guiding the latter in pivotal movement, a torsion spring having a pair of free ends one of which is secured to said clamp member and the other of which is secured to said lug, said spring being adapted to bias said clamp member which defines said movable channel inwardly toward said fixed channel, a transversely extending spring clamp secured to said base portion adjacent the rear end thereof, and said spring clamp being adapted to engage the edges of the sole of a shoe adjacent the rear shank portion thereof immediately forwardly of the forward edge of the heel of the shoe for retaining the shoe in proper shape.

2. A shoe form comprising a planar base portion of rigid material having a contour substantially the shape of a shoe sole, an upturned vertically extending flange formed integrally with said base portion along one edge thereof, said flange at its upper edge being bent inwardly of said base portion for defining a fixed channel, a clamp member pivotally mounted at its forward end to said base portion, said clamp member having formed integrally therewith an upturned vertically extending flange portion which at its upper end is bent inwardly for defining a movable channel, said fixed and movable channels converging toward the toe portion of said base, a torsion spring having a pair of free ends one of which is secured to said clamp member and the other of which is secured to said base portion, said spring being adapted to bias said clamp member which defines said movable channel inwardly toward said fixed channel, a transversely extending spring clamp secured to said base portion adjacent the rear end thereof, and said spring clamp being adapted to engage the edges of the sole of a shoe adjacent the rear shank portion thereof immediately forwardly of the forward edge of the heel of the shoe for retaining the shoe in proper shape.

BROTHER E. WALSTROM.
